UNITED STATES PATENT OFFICE.

WILLIAM L. HAINES AND ROBERT J. GRAY, JR., OF SAGINAW, MICHIGAN.

COLLAPSIBLE PACKAGE OR CRATE.

SPECIFICATION forming part of Letters Patent No. 767,051, dated August 9, 1904.

Application filed July 27, 1903. Serial No. 167,216. (No model.)

To all whom it may concern:

Be it known that we, WILLIAM L. HAINES and ROBERT J. GRAY, Jr., citizens of the United States, residing at Saginaw, in the county of Saginaw and State of Michigan, have invented a new and useful Folding or Collapsible Package or Crate, of which the following is a specification.

This invention relates to baskets or crates, and more particularly to that class that are collapsible, and has for its object the provision of a device of this character that will be simple and efficient in construction, as will be more fully hereinafter described, and illustrated in the accompanying drawings, in which—

Figure 1 is a perspective view of a crate embodying our invention. Fig. 2 is a top plan view thereof, and Fig. 3 is a fragmentary view showing details of construction.

Similar letters of reference indicate corresponding parts in the several views.

Our device is provided with wire sides and a hoop, preferably of wood, at the top and bottom, the bottom hoop supporting a perforated bottom plate and said bottom hoop being of less diameter than the top hoop. The top hoop A is provided with a series of suitably-spaced apertures a, while the bottom hoop D is provided at its upper edge with projections d, which form therebetween, when the bottom plate E is applied, elongated perforations C. The sides are composed of a series of wires B bent double upon themselves as a staple and terminating at both ends in circular eyes b, passing through the apertures a in the top hoop A, thereby giving a hinged connection. The doubled end b' of the wire is adapted to embrace one of the projections d of the bottom hoop D, and the wire itself is free to ride in the perforations C. In prac-

tice it has been found advantageous to have the projection d to lie normally between the apertures a of the top hoop, or, in other words, the ends of the perforations C to lie approximately in alinement with the apertures a.

In practice to fold the crate all that is necessary is to push the two hoops toward one another until the bottom hoop, being smaller, is within the top hoop. The side wires being hinged to the top hoop and free to ride through the bottom hoop will by this operation be brought to an approximately horizontal plane with the free or double ends extending toward the center of the hoops.

Having fully described the invention, what we claim as new, and desire to secure by Letters Patent, is—

A collapsible crate comprising two hoops of different diameters, the larger hoop having a series of apertures, and projections on the smaller hoop adapted to lie on a line between the apertures of the larger hoop, a series of wires connecting the two hoops, each wire being bent on itself; the free ends passing through the apertures of the larger hoops and forming hinges, the rounded end being adapted to embrace the projections on the smaller hoop, and a plate secured to the smaller hoop adapted to hold the rounded ends on said projections and forming elongated perforations through which the wires are free to ride.

In testimony whereof we have signed our names to this specification in the presence of two witnesses.

WILLIAM L. HAINES.
ROBERT J. GRAY, JR.
